UNITED STATES PATENT OFFICE

ARTHUR ATWATER KENT, OF ARDMORE, PENNSYLVANIA

RADIOSPEAKER

Application filed May 26, 1925. Serial No. 32,875.

My invention relates to telephonic apparatus, and particularly to amplifying telephones, loud speakers or radio speakers, utilized in connection with radio receiving apparatus.

In accordance with my invention, the electro-magnetic system comprises a field yoke or frame, preferably permanently magnetized, having on opposite sides poles of opposite signs, with inwardly projecting pole pieces, preferably separate from but secured to the yoke or frame, and flexible or yielding, with means carried by the frame or yoke for flexing the pole pieces to effect adjustment of the distance or air gap between them and the co-acting vibrating armature fixed at its one end to one side of the yoke or frame and extending preferably transversely to the longitudinal extent of the pole pieces.

Further in accordance with my invention, the adjustment of the pole pieces with respect to the vibratile armature is effected by structure of such character that as the pole pieces are deflected towards the armature, the armature simultaneously recedes from the pole pieces, but to lesser extent.

Further in accordance with my invention, the air-vibrating diaphragm or tympanum, of paper, metal or other suitable material, preferably of large area or diameter and preferably conical, is secured fixedly either directly to the vibratile member of the magnet system or upon a member which in turn is directly secured to the vibratile member of the magnet system; further in accordance with my invention, a stand or support for the instrument as a whole comprises a support to which the magnet system is secured, and the tympanum or diaphragm is carried by such support through the medium of the magnet system, and particularly the vibratile element thereof.

Further in accordance with my invention, the diaphragm or tympanum is secured or confined only at or adjacent its center, and at its periphery is entirely free, unsupported and undamped.

Further in accordance with my invention, there may be provided for the diaphragm or tympanum a shield or guard surrounding but

spaced from its periphery to leave it unsupported and free to vibrate thereat and to protect it from contact with other objects.

My invention resides in apparatus of the character hereinafter described and claimed. 55

For an illustration of one of the various forms my invention may take, reference is to be had to the accompanying drawing, in which:

Figure 1 is a front elevational view of structure embodying my invention, with a portion of the diaphragm cut away. 60

Fig. 2 is a vertical sectional view, partly in side elevation, of structure shown in Fig. 1.

Fig. 3 is a fragmentary vertical cross sectional view, partly in side elevation, on the line 3—3, Fig. 1, illustrating structure of the magnet system. 65

Fig. 4 is a fragmentary horizontal sectional view, partly in plan, taken on the line 4—4, Fig. 1, illustrating structure of the magnet system. 70

Fig. 5 is a side elevational view, partly in vertical section, illustrating the application of a housing or guard. 75

Referring to the drawings, 1 is a base or stand, to which is secured by screw 2 a bracket member 3, to which is secured the upwardly extending supporting member 4, to whose upper end is secured by screws 5 the open substantially rectangular frame or yoke 6 of the magnet system, suitable spacing members 7 being interposed between the yoke or frame 6 and the support 4 through holes in which the screws 5 extend and have applied thereto on the rear of the support 4 the nuts 8. 80

Secured to the yoke or frame 6 by the same screws 5 are the inwardly extending pole pieces 9, between whose ends is left an air gap. Surrounding the pole pieces 9 are the windings or coils C traversed by the voice- or sound-representing current, such as exists, for example, in the anode circuit of a detector or audio frequency amplifier as utilized commonly in radio receiving circuits, the flexible conductors c, c serving to connect the windings in circuit. As usual, the two windings or coils operate cumulatively with each other to simultaneously strengthen or weaken the magnetic field acting upon the vibratile mem- 100

ber 10. The yoke 6 is preferably permanently magnetized, having poles of opposite signs at opposite ends thereof adjacent the points of attachment of the soft iron or steel pole pieces 9, 9, whereby at the inner and adjacent ends of the pole pieces 9 are exhibited opposing north and south magnetic poles.

The vibratile member or armature of the magnetic system comprises the soft iron or steel bar or reed 10 secured by screw 11 to the yoke or frame 6 substantially midway between the points of attachment thereto of the pole pieces 9, or at a substantially neutral magnetic point or region of the frame 6. There preferably intervenes between the armature 10 and the frame 6 a washer 12, for spacing the lower or free end of the armature 10 from the pole pieces 9, and serving also as an abutment for the armature about which it may flex or bend under the influence of the sound-representing current.

Extending substantially parallel with the armature 10, but on the opposite side of the frame 6 therefrom, is the substantially rigid bar 13 secured to the yoke 6 by the screw 11. Adjacent the inner or free end of the bar 13, which may be of soft iron or steel or other suitable metal, there is threaded therethrough the adjusting screw 14 of brass, locked by the nut 15, and having a flat end engaging the pole pieces 9 to align them and to flex them to adjust the air gap between them and the armature 10.

Threaded into or otherwise fixedly secured to the vibratile member 10 is the pin or rod 16, to which is fixedly secured the air-vibrating member, diaphragm or tympanum.

The tympanum or diaphragm 17, in the form of a cone, and of relatively large diameter, preferably upwards of six inches, is provided exteriorly and interiorly at its apex with the metal reinforcing conical members 18 and 19, to which is secured the bushing 20, through which extends the rod or pin 16, against which is set the screw 21 threaded in the bushing 20, whereby the cone or diaphragm is fixedly secured and supported solely by the vibratile member or armature 10, through which and the magnet system the diaphragm or cone is supported upon the bracket or supporting member 4.

While, as indicated in Fig. 2, the cone may be so placed upon the rod 16 that the support 4 and the magnet system are disposed within the cone, it will be understood that, as indicated in dotted lines, the diaphragm or cone may be reversely placed upon the pin 16, particularly since the periphery of the diaphragm or cone is left entirely unsupported and free to vibrate.

In operation, the lower or free end of the armature 10 is suitably spaced by air gap from and bridges the inner ends of the pole pieces 9, which exert upon the armature 10 a magnetic attraction which is varied in accord-

ance with the voice- or sound-representing current, with the result that the member 10 vibrates in accord with the current variations and with an amplitude depending upon the amplitude of the current. The vibrations of the armature 10 are communicated to the conical tympanum through the rod or pin 16, if utilized, or directly to the tympanum if the latter is directly or immediately secured upon the armature 10. The cone 17 vibrates axially and to considerable extent radially, particularly when the rod or pin 16 is utilized, and when the cone is attached to the rod 16 at considerable distance from the armature 10. This vibration transversely to the axis of the cone is substantially in the plane of the paper, Fig. 2, and is substantially nil in a plane at right angles thereto.

For both axial and transverse vibration the cone is unrestricted throughout and free to vibrate at its extreme periphery at the frequency and with the amplitude of vibrations transmitted through the cone from its axis or center, whereat only it is secured or fixed to and comprehended in the vibratory system comprising in addition the vibratory armature 10.

As indicated, the point of attachment of the cone 17 or its supporting pin or rod 16 to the armature 10 may be disposed to some extent nearer the supporting screw 11 than the center of the pole pieces 9. However, such point of attachment may be otherwise located, to accord with the diameter or area of the diaphragm or cone.

To effect adjustment of the distance or air gap between the ends of the pole pieces 9 and the armature 10, the adjusting screw 14 is rotated, when the lock nut 15 is loosened, inward movement of the screw 14, which at its flat end engages both pole pieces 9 and serves to align their lateral surfaces, causing flexure of the pole pieces toward the left, Fig. 3, the reaction also flexing the frame or yoke 6, and causing the free or lower end of the armature 10 simultaneously to move away from the pole pieces 9, but to lesser extent than the ends of the pole pieces 9 are forced toward the armature 10, whereby in effect the resultant adjustment is fine or nice, because of the differential effect procured.

To shield or guard the cone or diaphragm 17, which may be constituted of paper or of thin sheet metal, as aluminum, brass, etc., there may be provided the housing, shield or guard structure 22, Fig. 5, extending around the periphery of the diaphragm or cone, and extending also to either or both sides of the periphery, but always substantially spaced therefrom to permit free vibration of the cone throughout and at its periphery. The shield or housing structure 22 may be of sheet metal having the several arms 23 radiating outwardly and extending axially

from the central supporting member 4 to which the magnet system is secured.

What I claim is:

1. A telephone magnet system for actuating a sound-reproducing diaphragm of large area comprising a magnet frame, pole pieces therefor extending from opposite sides of said frame intermediate the ends thereof and having their inner ends spaced from each other, a vibratile armature bar secured adjacent its one end to said magnet frame and having its free end disposed adjacent the inner ends of said pole pieces and bridging the gap between them, and a diaphragm-actuating member operated by said vibratile bar.

2. A telephone magnet system comprising a permanently magnetized and circumferentially continuous magnet frame, pole pieces therefor extending from opposite sides of said frame and having their inner ends spaced from each other, windings on said pole pieces traversed by sound-representing current, and a vibratile armature bar secured adjacent its one end to said magnet frame and having its free end disposed adjacent the inner ends of said pole pieces and bridging the gap between them.

3. A telephone magnet system comprising a magnet frame, pole pieces therefor, means carried by said frame and engaging said pole pieces to effect their alignment with each other, and a vibratile armature reed co-acting with said pole pieces.

4. A telephone magnet system comprising a magnet frame, flexible pole pieces therefor, a vibratile reed-armature co-acting with said pole pieces, and an adjustable member carried by said frame engaging said pole pieces and to flex them with respect to said armature.

5. A telephone magnet system comprising a magnet frame, pole pieces therefor, a vibratile reed-armature co-acting with said pole pieces, a bar secured to said magnet frame and extending toward said pole pieces, and an adjusting screw carried by said bar and engaging said pole pieces to effect their alignment with each other.

6. A telephone magnet system comprising a magnet frame, flexible pole pieces therefor, a vibratile reed-armature co-acting with said pole pieces, a bar secured to said magnet frame and extending toward said pole pieces, and an adjusting screw carried by said bar and engaging said pole pieces to effect their alignment with each other and to flex them with respect to said armature.

7. A telephone magnet system comprising a magnet frame, flexible pole pieces therefor, a vibratile armature carried by said frame and co-acting with said pole pieces, and an adjusting member carried by said frame engaging said pole pieces to flex them toward said armature and reacting through said frame to cause said armature to recede from

said pole pieces to lesser extent than said pole pieces are flexed toward said armature.

8. A telephone magnet system comprising a magnet frame, pole pieces therefor, a vibratile armature bar secured adjacent its one end to said magnet frame and having its free end disposed adjacent said pole pieces, a second bar secured to said magnet frame adjacent the attachment thereto of said armature bar, and an adjusting screw carried by said second named bar engaging said pole pieces to effect their alignment with each other.

9. A telephone magnet system comprising a magnet frame, flexible pole pieces therefor, a vibratile armature bar having its free end disposed adjacent said pole pieces, a second bar, means common to said bars for securing them to said magnet frame, and an adjusting screw carried by said second named bar and engaging said pole pieces to flex them.

10. A telephone magnet system comprising a magnet frame, pole pieces secured to the same face of said magnet frame, a vibratile armature bar having its free end disposed adjacent said pole pieces, means for securing said armature bar adjacent its other end to said magnet frame on said face thereof, and means for spacing said other end of said armature bar from said face of said magnet frame.

11. A telephone magnet system comprising a supporting member, a magnet frame, pole pieces therefor, a vibratile armature co-acting with said pole pieces, and means comprising a plurality of screws all common to said supporting member, magnet frame and pole pieces for holding them in assembled relation.

12. A telephone magnet system comprising a supporting member, a magnet frame, spacing members interposed between said supporting member and frame, pole pieces for said magnet frame, a vibratile armature co-acting with said pole pieces, and means comprising a plurality of members traversing said spacing members and common to said supporting member, magnet frame and pole pieces for holding them in assembled relation.

13. A sound amplifier comprising a stand, a support carried thereby, said support having an open peripheral beading, a large direct acting vibratory diaphragm of conoidal form disposed entirely free and unconfined in said beading, said diaphragm being of non-metallic material, a sound-reproducing instrumentality carried by said support, and means operatively connecting said instrumentality with the apex of said diaphragm.

14. The combination with a reproducer actuated by current variations produced by sound, of a hollow conoidal diaphragm, means for adjustably supporting said diaphragm at its apex, the base of the dia-

phragm being entirely free and unconfined, said supporting means also communicating vibrations from the reproducer to the diaphragm.

15. A telephone magnet system comprising a permanently magnetized and circumferentially continuous magnet frame, a vibratile armature bar secured adjacent its one end to said magnet frame, the free end thereof terminating short of the opposite side of said frame, and pole pieces extending from opposite sides of said frame and having their inner ends spaced from each other to form a gap bridged by said free end of said vibratile bar.

16. A telephone magnet system comprising a permanently magnetized and circumferentially continuous magnet frame, a vibratile armature bar secured adjacent its one end to said magnet frame, the free end thereof terminating short of the opposite side of said frame, and pole pieces extending from opposite sides of said frame and substantially at right angles to said vibratile armature bar which bridges a gap between spaced inner ends of said pole pieces.

17. A sound amplifier comprising a stand, a support carried thereby, said support having an open peripheral beading, a large direct 30 acting vibratory diaphragm of conoidal form loosely disposed in said beading, said diaphragm being of non-metallic material, a sound reproducing instrumentality carried by said support, and means operatively connecting said instrumentality with the apex of said diaphragm.

18. The combination with a reproducer actuated by current vibrations produced by sound, of a hollow conoidal diaphragm, 40 means for adjustably supporting said diaphragm at its apex in a vertical plane, the base of the diaphragm being entirely free and unconfined, said supporting means also communicating vibrations from the reproducer to the diaphragm.

19. A sound amplifier comprising a stand, an arm raised from said stand, a reproducing instrumentality fixed at the end of said arm, and an amplifying diaphragm supported in 50 a vertical plane and actuated directly by said instrumentality, said diaphragm being wholly free and unrestrained.

20. A sound amplifier comprising a stand, an arm extending from said stand, a sound 55 reproducing device supported by said arm, a rod supported by said sound reproducing device, and a conoidal diaphragm operatively fixed at its apex on said rod to be supported and vibrated thereby, said diaphragm being otherwise unconfined.

21. An amplifying telephone comprising a support, a telephone magnet system carried by said support and comprising a vibratile armature and pole pieces, a conical dia- 65 phragm of large diameter vibrated by said

armature, and a rotatable adjusting member for adjusting the air gap between said pole pieces and armature, said member having means disposed within the control dia- 70 phragm for manually operating said member.

CERTIFICATE OF CORRECTION.

Patent No. 1,794,855.

Granted March 3, 1931, to

ARTHUR ATWATER KENT.

It is hereby certified that error appears in the printed specification of the above numbered patent requiring correction as follows: Page 4, line 69, claim 21, for the word "control" read conical; and that the said Letters Patent should be read with this correction therein that the same may conform to the record of the case in the Patent Office.

Signed and sealed this 31st day of March, A. D. 1931.

M. J. Moore,
Acting Commissioner of Patents.
